UNITED STATES PATENT OFFICE.

ELMER G. HOOPER, OF NEW YORK, N. Y.

PAVEMENT FOR HIGHWAYS.

Application filed November 1, 1922. Serial No. 598,344.

To all whom it may concern:

Be it known that I, ELMER G. HOOPER, citizen of the United States of America, residing at 420 East 239th Street, New York city, in the county of Bronx and State of New York, have invented certain new and useful Improvements in Pavement for Highways, of which the following is a specification.

10 This invention relates to highways, and has special reference to a pavement for highways.

It is to be understood that the use of the terms highways and pavement throughout this specification and claims are not to be restricted to the precise definition of these words, but the term "highways" is to be read as sufficiently broad to cover all roadways, courtyards, and other like places both public and restricted which are intended primarily to carry vehicular traffic. Also the term "pavement" as used herein is to be read throughout as broad enough to cover not only the surface on which the traffic passes, 25 but the substructure or artificial permanent foundation on which may be laid surface.

In order that the purpose of the invention may be clearly appreciated, it is expedient to explain briefly the requirements of the 30 modern highway.

Because of the great developments of the motor vehicle, and the intensive use of the same in transportation over the highways and roads the requirement has arisen for 35 permanent, hard, smooth pavements for such highways. The developments of the motor units in number, weight and speed has been such that the design and construction of highway surfaces, to fulfill the 40 above requirements, has not kept pace. Among the reasons for the present lack of developments of highway surfaces or pavements has been the fact that the soil usually met with on or near a highway has not, as a 45 rule, been found susceptible to treatment that would satisfy the requirement of permanency, and in consequence, it has been the practice to design some artificial structure having a limited ability to resist the 50 rupture from stretching or compressing

and to place such structure upon the natural ground, prepared or treated, to a greater or less degree, to support it.

When such an artificial structure is first placed upon the ground, assuming that the proper care has been taken, it is most probably uniformly supported throughout and conforms in shape to the soil surface as prepared for the structure. This condition is found to last but a short time with the result that the structure is subjected to stresses different in kind and amount than those for which it was intended. The magnitude of such stresses cannot be predetermined because of the fact that moisture and 65 temperature conditions cause very wide variations in the action of the soils beneath the artificial surfaces or pavements. For instance, moisture runs off of the structure, soaks into the soil along the edges, and with soil thus moistened a certain expansion takes place which tends to lift the structure by the edges so that the sustaining of the structure by the soil at the middle is lessened, and the tendency is for 70 the structure to sag at the middle thus compressing the surface and stretching the underpart. Furthermore, other conditions may arise wherein the surface structure or pavement will be supported principally at 75 the middle, and thus there will be a tendency to sag on the edges with consequent stretching of the upper part of the pavement and compression of the lower. Obviously, if either of these conditions prevail, 80 the weight of a motor vehicle and its load running over such pavement produces rapid disintegration of the pavement structure.

Heretofore it has been customary to so design the pavement structure that the intent is to support the same throughout its entire length and breadth, and it has been also customary, especially in precasting or forming pavement structures, to form such structures as rectangular blocks or sheets, 85 and to pay especial attention to the support of the same at the corners. Under such conditions, if the support at any corner is lessened, it is impossible, in practice, to determine what stresses will be brought by 90 100

a load at any portion of the slab or pavement. If, however, the structure be designed to rest on three supports, moderate settlement of any or all of them will affect 5 the stresses to only a slight degree.

One important object of the invention is to provide a novel form of highway surface or pavement to which is applied, in the design, this principle of three supports, the 10 invention also contemplating the construction of reenforced concrete slab units or slab units of other rigid material so designed as to render themselves readily to a three point support.

15 In a preferred embodiment of the invention, the slabs referred to are given the formation of triangles of substantial size such that two or three or other small number of slab units extends across the full 20 width of the roadway. By arranging such slabs in an edge to edge formation with a rigid support at the apices it will be seen that I obtain the full advantage as to stability arising out of the three-point-support 25 such as is typified by the well known three-legged-stool effect. The arrangement of the slabs in the edge to edge relation referred to gives rise to the grouping of six apices of as many slabs at a common point so that 30 but a single support is needed for the group.

The term "point" as used throughout the case is intended to mean a surface or area that is relatively small as compared with the superficial area of one of the paving 35 slabs. For instance as disclosed in the drawing a point represents the area of contact between a slab and the top of a supporting post, pile or other support presenting a relatively small area of contacting engagement 40 with the slab. The term "line" in the same connection is intended to mean an area of relatively great length as compared to its width as illustrated by the top edge of a beam, curb or the like.

45 The expression "three-point-support" is therefore intended to mean the support of pavement units or slabs on three points so arranged that only two of the points lie in the same vertical plane. Similar results 50 may also be obtained by replacing two of the point supports by a line support so that the three-point-support is intended to include support on one line and one point not in the same vertical plane with the line.

55 In this respect, it is to be understood that by a three point support of such a device as a triangular slab, the term "three point support" or other like term is not to be taken literally throughout this specification, 60 but is to be understood as broad enough to include also the support of a triangular slab along one edge and at the opposite angle, this being the full equivalent, for the purpose, of a three point support. Consequent-

ly, when such term is used in the specification and claims, it is to be read as broad enough to include both forms.

Even though the settlement of such three point supports may not seriously increase the stresses in the slabs, such settlement of 70 a single support would tend to make the general pavement surface warped at joints and unpleasant to ride over.

A second important object of the invention is to provide an improved construction 75 of highway pavement wherein the latter will be supported on suitable posts or piles of concrete, plain or reenforced with metal, metal, or other solid and durable material, placed upon, or driven to a soil stratum of 80 satisfactory bearing power, at or below the so-called frost level, or to solid rock, the posts or piles being so arranged as to act as supports for the slabs to rest upon.

85 A third important object of the invention is to provide suitable means for connecting the slabs to the supporting posts, such means being so designed and arranged as to permit only slight lateral movement for temperature changes, but freely permitting the jacking or raising of the slabs off of the supports, and placing of so-called shims in order to level up the pavement in the event of the same being distorted by climatic or 90 temperature conditions.

95 The passing of a load over such a pavement thus constructed has the effect of tending to cause a sag in the slab carrying it, so that its surface at the joint would be below the adjoining slab temporarily, and in passing over the joint, the vehicle would bump up, causing undue stress in that next slab, or the slabs would have to be overdesigned.

100 A fourth important object of the invention is to provide, in such a pavement, interlocking joints, so designed as to lock the adjacent slabs together along their edges, and thus make adjoining edges sag equally or approximately the same amount. This will cause a wider distribution of stresses from a given load, and consequently, will enable economy to be effected in design.

105 A fifth important object of the invention is to provide for the precasting, in molds, of the separate slab units and to have them placed in position on the pavement foundation after proper seasoning. This method will permit making and storing of slabs in shelter so work may be continued on this part during storm and bad weather. It will permit rapid laying of slabs and cause less interruption of traffic, to allow seasoning. Thus transportation of the slabs from the central yard to their final position may be over the finished surface as fast as the latter 110 is laid. Spare slabs may be kept in stock for replacement, since it is the intent that 115

the design of dowels and lock joints is such as to permit removal of a slab or slabs at any time, for excavation beneath, or for replacement, possibly made necessary by injury.

With the above and other objects in view as will be hereinafter apparent, the invention consists in general of certain novel details of construction and combination of parts hereinafter fully described, illustrated in the accompanying drawings and specifically claimed.

In the accompanying drawings, like characters of reference indicate like parts in the several views, and :-

Fig. 1 is a plan view of a section of a pavement constructed in accordance with this invention;

Fig. 2 is a perspective view of one of the units of such a pavement;

Fig. 3 is an enlarged detail section on the line 3-3 of Fig. 1;

Fig. 4 is a detail view of one of the dowel pins used herewith;

Fig. 5 is a detail view showing the connection of one of the slabs to one of its supporting posts;

Fig. 6 is a view showing portions of two adjoining slabs at one of the angles of the triangle.

In carrying out the invention, there is first of all provided a series of piles or posts 10, which are preferably placed with their centers at the corners of triangles. In the central part of the pavement these posts are preferably circular in cross section, although they may be hexagonal or any other convenient shape, the object being to provide for the support of the angles of six slabs. At the edges of the pavement, the posts are preferably semi-circular in cross section so as to support three adjacent angular portions of the slabs. Each of these posts in the center is provided with six dowel pin receiving openings 11 wherein fit the dowel pins 12. At the sides, there are in like manner, three of these dowel pin receiving openings to receive the corresponding number of dowel pins. Each of the slabs is preferably made of reenforced concrete, and is of general triangular form, as shown at 13, the slabs being provided at their corners with dowel pin receiving openings 14 wherein are received the upper ends of the pins 12. Furthermore, each edge of each slab is provided at its upper or its lower surface with a recess 15, adjacent to which is a projecting lip 16, the lip of one slab fitting the recess of the adjacent slab. By this means the slabs are given a three point support, and adjacent slabs are locked together so that any depression of an edge of one of these slabs will tend to depress the adjacent edge of the next slab thus distrib-

uting the stresses as previously set forth. It is obvious that in place of the semi-circular edge post or piles 10, a curb may be laid such as is shown in Fig. 1 at 17, this curb serving to support the entire edge, and in some instances, it will be found advantageous to thus construct the pavement.

It is expedient to give a typical design of a single slab unit, of reinforced concrete, illustrative of the method proposed. The methods of calculation, data, and arrangement of material used is reasonably justified by present day knowledge of principles and of facts, but by use of said method of calculation, data and arrangement of material, it is not intended to limit the design, since it is hoped that more experience and experiment may show ways of improvement. The claims made with reference to design of slab and its placing are basic and are not affected by change in data or in arrangement of material.

It is proposed to place steel in such position and in such quantity as to take up all tension. Concrete of fine quality will be used to take up compressive stresses. Concrete in most cases is sufficient to care for shear but some rods may be bent to take diagonal tension.

Inasmuch as simplicity of construction methods is necessary for economy, the slab unit, considered for calculation, is taken of uniform thickness throughout, and the critical section, as at the middle of the edge of slab receiving no support from an adjacent one, that is, the edge next the shoulder of the road. The loading considered is the weight of a loaded truck, totalling thirty thousand pounds, increased by twenty five per cent for impact; thirty five per cent of this is carried by each rear wheel spaced six feet apart on centers of thirteen inch treads or tires. This loading corresponds to the maximum allowed at the present day. The position of said loaded truck for maximum bending, at the critical section above referred to, gives a loading of thirteen thousand one hundred pounds at that section. Stresses in steel reinforcing are considered safe up to the elastic limit but some value under that, say thirty thousand pounds per square inch, is preferred, in order that deflections may not be excessive. Stresses in concrete are considered safe when not exceeding sixty per cent of the ultimate strength, that is, for concrete having an ultimate strength of thirty five hundred pounds per square inch after twenty eight days, an indefinitely repeated compressive stress up to twenty one hundred pounds per square inch is allowed. For the values of allowed stress, noted above, a design having one and one quarter per cent reinforcement is safe when the computed steel stresses are

satisfactory, since stresses in the concrete will fall below that allowed.

The nomenclature adopted is quite commonly used, and, where not specifically defined, is considered as having a meaning given, or implied, in the text book "Principles of Reinforced Concrete Construction" by Turneaure and Maurer.

P, ratio of steel area to effective concrete area-----
 n , ratio of moduli of elasticity, steel to concrete-----
 r , ratio of allowable to maximum concrete stress-----
 d , effective thickness of slab-----
 D , total thickness of slab-----

b , effective breadth of slab acting as a beam at a given time.	
W_1 , wheel load plus impact-----	13100.0 lbs.
W_2 , weight of slab unit-----	4250.0 lbs. 29
M , maximum live load bending moment.	
M_1 , maximum dead load bending moment.	
m_1 , resisting moment of slab per inch width.	25
m_2 , resisting moment of slab per inch width effective against live load bending moment.	30
l , unsupported span, or beam length -----	8.85

$$1. m_1 = pd^2/s_s \\ = 0.0125 \times 36 \times .85 \times 30,000 = 11,480 \text{ inch pounds.}$$

$$2. M_1 = \frac{W_2}{3} \times \frac{1}{2}$$

$$= \frac{4250 \times 8.85 \times 12}{3 \times 2} = 75,300 \text{ inch pounds.}$$

Width of cross section to resist M_1 72".
 Dead load moment per inch width 1040 inc.

$$3. m_2 = 11,480 - 1040 = 10,440 \text{ inch pounds.}$$

$$4. M = \frac{W_1}{2} \times \frac{1}{2}$$

$$= \frac{13,100 \times 8.85 \times 12}{2 \times 2} = 348,000 \text{ inch pounds.}$$

$$5. b = \frac{M}{m_2}$$

$$= \frac{348,000}{10,440} = 33.4"$$

The calculations are not complete, but are sufficient to show approximate methods.

35 Because a new invention is dealt with, the application of old principles to the design must necessarily be susceptible of correction or adjustment after experience and experiment show the way.

40 From the foregoing it will be seen that a highly effective pavement is provided, which may be cheaply and economically installed, bearing in mind the permanency and supporting qualities of the pavement.

45 Having thus described the invention, what is claimed as new, is:-

1. In a pavement of the class described, a series of supporting posts arranged at the apices of triangles, and supporting slabs of triangular form having their apices resting on said supporting posts.

50 2. In a pavement of the class described, a series of supporting posts arranged at the apices of triangles, supporting slabs of triangular form having their apices resting on

said supporting posts, and secured thereto against slipping therefrom.

3. In a pavement of the class described, a series of supporting posts arranged at the apices of triangles, loose dowel pins extending upward from said posts, and triangular formed slabs resting on said posts at their angles, and having openings therein to receive said dowel pins.

4. In a pavement of the class described, a series of triangular slabs arranged edge to edge, the apices of the triangles of adjacent slabs meeting in a common point, and supporting means in said apices, said slabs being interlocked along their edges to prevent independent vertical movement.

5. In a pavement of the class described, a series of supporting posts arranged at the apices of triangles, supporting slabs of triangular form having their apices resting on said supporting posts, said slabs being interlocked along their edges to prevent independent vertical movement.

6. In a pavement of the class described, a series of supporting posts arranged at the apices of triangles, supporting slabs of triangular form having their apices resting on said supporting posts, and secured thereto against slipping therefrom, said slabs being interlocked along their edges to prevent independent vertical movement.
7. In a pavement of the class described, a series of supporting posts arranged at the apices of triangles, loose dowel pins extending upward from said posts, triangular formed slabs resting on said posts at their angles and having openings therein to receive said dowel pins, said slabs being interlocked along their edges to prevent independent vertical movement.
8. In a pavement of the class described, a series of supporting posts arranged at the apices of triangles, loose dowel pins extending upward from said posts, triangular formed slabs resting on said posts at their angles and having openings therein to receive said dowel pins, said slabs being interlocked along their edges to prevent independent vertical movement, the interlocking means being designed to permit unlocking by lateral movement of one slab relative to the other.
9. In a pavement of the class described, a series of supporting posts arranged at the apices of the triangles, loose dowel pins extending upward from said posts, triangular formed slabs resting on said posts at their angles, and having openings to receive said dowel pins, said slabs having complementary lips and recesses in their abutting edges, said lips and recesses forming interlocking means, the angle at the ends of the lips and recesses with the edge of the slab being such that any slab may be removed from lock after removal of its dowels by a slight lateral movement approximately normal to the free edge of such slab.

In testimony whereof I hereunto affix my signature.

ELMER G. HOOPER.
